UNITED STATES PATENT OFFICE.

GROVER C. STACY, OF DALLAS, TEXAS.

COTTON-CLEANER AND BOLL-BREAKER.

1,397,257.

Specification of Letters Patent. Patented Nov. 15, 1921.

Application filed February 19, 1920. Serial No. 359,761.

To all whom it may concern:

Be it known that I, GROVER C. STACY, a citizen of the United States of America, residing at Dallas, in the county of Dallas, 5 and State of Texas, have invented certain new and useful Improvements in Cotton-Cleaners and Boll-Breakers, of which the following is a specification.

My invention relates to an apparatus for 10 cleaning cotton and breaking bolls, and has for its object to design an apparatus possessing many novel features in its construction, the purpose of which is to simplify the assembling, dismounting and replacement of 15 parts and for inspecting and adjusting them.

My invention contemplates the provision 20 of a cleaner casing interposed in the suction feed line for the gins, and in the cleaner casing I interpose a series of rotating bladed shafts having blades of a special construction which forms the subject matter of a 25 separate application, Serial No. 349,449, filed the 5th day of January, 1920. These blades work over a screening concave carried by 30 a detachable or demountable bed and by demountable cross bolts.

I claim as one special feature of my invention this demountable screen bed frame and the arrangement of the baffle boards be- 35 low it, and of the refuse collecting pockets.

Another feature of my invention is the provision of removable screen slides forming 40 said pockets, these slides being removable through a side door in order to drop the larger refuse which has collected thereon 45 into the hopper bottom of the cleaner casing, and said door giving access to the under side of the screen concave to permit the lint cotton adhering to its under side to be cleaned 50 off and knocked down into the hopper.

A further important feature of my invention is the incorporation in the cleaner of a 55 boll breaking attachment adjustable with relation to the initial series of rotating blades and comprising a series of fingers which swing upwardly to the desired point between the rotating blades. As these breaker fingers approach the level of the beater shaft they increase the boll breaking 60 action of the apparatus and as they drop away the boll breaking action is reduced.

Another feature of my invention is the 65 peculiar shape of the breaker fingers which are diamond shaped in cross section with 70 their long axes vertically midway between the adjacent running blades and thus their

upper sloping faces have a tendency to direct the bolls into the path of the blades on each side.

Another feature of my invention is the 80 arrangement of the boll breaker at the intake end of the cleaner casing, thereby causing the broken pieces of bolls to be collected and separated during the passage of the cotton with the broken bolls through the 85 cleaner.

Another feature of my invention is the provision of removable side and top doors 90 opposite the blade shafts, thus permitting the machine to be opened up for access, inspection and repair of such parts, or for reversing them for right or left hand drive without requiring any dismounting of the casing. Also I claim especial advantages 95 for a removable glass door through which I 100 can inspect and readily clean the bottom of the screen concave of lint cotton and remove the screen bottom slides of the concave pockets.

My invention also comprises the details of 105 construction and arrangements of parts, which in their preferred embodiment only are illustrated in the accompanying drawings, in which:—

Figure 1 shows my apparatus in plan with 110 the side doors and top doors removed.

Fig. 2 is a side elevation of Fig. 1, one end of the machine being shown in vertical section on the line 2—2 of Fig. 1.

Fig. 3 is an enlarged sectional view taken 115 on the line 3—3 of Fig. 2 showing the boll breaker in its lowered position on the screen.

Figs. 4 and 5 show detail plan and end views of the removable top door.

Figs. 6 and 7 are sectional and elevation 118 views of the removable slide door.

Figs. 8 and 9 are detail views of the boll breaker shaft bearing and adjustable ports.

Fig. 10 is a detached detail view of the 120 removable screen bed showing the screen partly in place.

Fig. 11 is a partial side view showing the 125 glass door broken away to illustrate the manner of removing a slide bottom of a screen pocket.

Fig. 12 is a sectional view taken on the 130 line 12—12 of Fig. 11.

Similar reference numerals refer to similar parts throughout the drawings.

In the embodiment of my invention illus- 135 trated in the drawings, I show a cleaner casing interposed in the suction feed line 1

of the gin, the casing comprising a flaring intake connection 2 at one end and a similar discharge connection 3 at the opposite end. The connections 2 and 3 are provided with 5 marginal flanges which are secured to the end frame 4 at each end of the casing, which frame is formed of rectangular boards rigidly and securely fastened together. The end frames 4 are connected at each side at 10 the bottom by horizontal beams 5 and these are cross braced at intervals by transverse bolts 6, which, in the manner later described, serve in part to support the screen concaves. Below the rectangular structure formed by 15 the beams 5 and the end frames is a hopper 7, the walls of which converge toward a bottom discharge door 8 normally held closed by suction.

A separate screen bed shown in Fig. 10 20 is adapted to be inserted in the casing and to be supported at the top of the hopper 7 by the engagement of its reversely sloping end boards 9 with the sloping end walls of the hopper. These end boards 9 are connected by side boards 10 having pockets formed along their upper edges by curved walls 11 terminating at their bases in straight sloping walls 12 which receive cross boards 13 that are mortised into the boards 25 10. The boards 13 are arranged in reversely sloping juxtaposed pairs to form pockets and the boards of each pocket having slide grooves 14 for the reception of a screen sliding bottom 15 for the pocket which is removable laterally from the casing in the manner 30 hereinafter described. The high point between each pair of reversely curved walls 11 of the side boards stand immediately under a cross connecting bolt 6, as is better shown 35 in Figs. 2 and 10.

The removable screen bed carries a series 40 of depending baffle boards 16 having the same slope and extending to the same level as the left hand end board 9 of Fig. 10 with 45 which they are parallel and it is also provided with a series of shorter baffle boards 17 parallel with the right hand end board 9 and arranged so that each forms with the adjacent reversely sloping board 9 or 16, as 50 the case may be, a contracted outlet 18 through which the foreign matter sifting through the screen bed proper will work its way into the hopper 7 of the casing. It will be noted that each pair of adjacent 55 baffles 16, 17 converges upwardly toward its respective pocket formed by the walls 13 and 15, and the most important purpose of these baffle boards is to concentrate the up draft on the screen bottoms of the pockets so that 60 any cotton that has fallen therein when the gin suction was interrupted will be instantly picked up and carried off with the cotton flowing through the cleaner to the gin. Moreover, these baffles prevent eddies and cross 65 currents in the hopper.

The screen bed is made up of sections of foraminous sheeting, either perforated metal sheets, hardware cloth, or the like, and the sections are fastened along the top edges of the bed frame sides 10 which thus hold them 70 stretched across the machine. One screening section comprising the parts 19 and 19^a starts from the right hand end of Fig. 2 and passes down the concave edges 11 and stops at the edge of the slide groove 14 in the first cross board 13, being screwed or otherwise attached to the frame and board in any suitable manner. The second screening section 20 starts from the groove 14 on the 80 opposite side of the pocket, extends upwardly over the board 13 and follows up the adjacent concave walls 11 and passes over the bolt 6 and turns down the next concave walls 11 and terminates at the groove 14 in the board 13 of the second pocket. In this manner the screen bed is formed of sections assembled in the manner described. The screen bed under the boll breaker, which will be later described, is preferably formed by a screening section 19^a, see Fig. 3, which is 90 similar to 19 except that a series of longitudinal pockets or indentations 21 are formed therein to receive the boll breaker blades 22.

The boll breaker is preferably formed as an integral casting comprising a shaft 23 and 95 a series of parallel breaker blades 22 which are diamond shaped in cross section. The ends of the shaft fit snugly between the side walls of the removable bed frame and one end is provided with a square countersunk 100 end hole to receive the gudgeon pin 24 which projects through and turns in one side wall 25 of the casing, the other end of the breaker shaft being reduced to form a bearing with its outer end squared to receive an 105 operating crank 26. This crank has hinged thereto by a pin an operating arm 27 which passes down through a guide bracket 28 near the bottom of the casing and is adapted to be 110 adjustably positioned by a set screw 29. 110 working through the bracket and engaging in one of a series of adjustment holes in the arm. A stop pin 30 (see Fig. 9) on the casing arrests the crank arm when the breaker arms are in their extreme raised position. When in lowered position, the breaker arms lie snugly in the pockets 21 of the screen section 19^a.

The casing proper is provided at each end with short side walls 25 and these side walls are braced overhead by bars 31 which stop about midway between the end frames and the center of the casing and are braced by vertical bars 32 to the bars 5. These bars 31 are connected overhead at each end of the 120 casing by a top section 33. The permanently attached side walls 25 and top walls 33 are thus interrupted to leave the whole middle section of the casing free to be exposed overhead. The chief object of this is 125 130

to provide for the removal of all casing parts above or opposite the operating mechanism in the cleaner.

The operating mechanism in the cleaner 5 comprises a plurality of cross shafts 34, each mounted in its respective bearings 35 which are bolted on the beams 5 removable, see Fig. 7. Pulleys 36 are fast on corresponding ends of the shafts 34 which overhang from 10 the casing and are all driven in the same direction by a belt 37. The portion of the shafts lying between the side walls has mounted thereon a series of beaters 38 which form the subject matter of a separate application 15 and are herein briefly described as comprising a star shaped arrangement of thin star shaped blades mounted centrally around elongated hubs 39 which abut to space them on the shafts 34 on which they 20 are fast. I have shown three shafts 34 with the beaters relatively staggered on adjacent shafts. The middle shaft with the smaller number of beaters has end collars 40, and these collars and the end hubs on the other 25 shafts form a close running joint with the side walls of the casing to prevent objectionable air leakage.

The beaters turn on centers substantially concentric with the curve of the screen 30 concaves and the blade tips describe a circle close to these screen bottoms of the concaves. Preferably the circles described by the blades, as viewed in side elevation, do not overlap.

35 The openings left in the side and top walls opposite the operating mechanism are closed by a batten top door 41 and by side doors 42 having top bars 43. The end walls 25 and their top bars 31 are cut away so as to 40 form a slip lap joint (see Fig. 6) with the correspondingly cut away edges of the door 42 and the top bar 43 thereon, and at their base the doors 42 are provided with round notches 44 to fit over the shafts 34. A removable pin 56 holds the joint parts assembled. The doors 42 and side walls 25 form on the inside continuous smooth side walls (see Fig. 5) practically free of air 45 leaks from end to end of the casing.

50 The top section 33, adjacent to the intake end of the machine, has a hinged screen deflector 45 connected to its under side by a cross hinge rod 46 (see Fig. 3) which projects through the side walls 25 and top bars 55 31 at one end carries a crank 47 pivoted to an operating rod 48 which drops down into a position to be handled from the floor and adjusted to set the deflector at any desired angle. The rod works through a bracket 60 28 and is set in adjusted positions by a set screw 29 as desired in connection with the rod 27.

One side wall 49 of the hopper immediately below the beam 5 is cut away to form 65 a long narrow opening 50 normally closed by

a glass door 51 which is normally held in place by clamps 52. By removing this glass door the screen bottom sides 15 can be drawn out so as to drop into the hopper bottom of the casing all large refuse and foreign 70 matter that has collected in the pockets and access can be had through the hand holes 53 in the sides 10 of the screen bed frame to clean off all lint adhering to the under face of the screens.

In operation, having mounted the heater shafts in the manner described, and set in place the side and top doors of the casing, as well as the glass door 51, the apparatus 75 is ready for service and power to drive the beater shafts is transmitted by a belt 54 or any other suitable source of power to a pulley 55 on one of the shafts 34 at the opposite end from the pulley 36 thereon. The driving shaft 34, carrying the pulley 55, 80 can be arranged at either end of the machine. The blades turn in a direction to drive the incoming cotton toward the screen bed and, assuming the breaker blades to be adjusted to lowered position in the screen 85 pockets 21, the cotton is deflected downwardly by the deflector 45 and is caught by the blades of the first beaters and whipped over the first screen concave. As the cotton 90 rides up the far side of the concave it 95 works over the hump in the screen above the first cross bolt 6 and as it falls over this hump it is inverted and caught by the second series of blades and is whipped over the second concave, it being a special feature 100 of my construction that the cotton inverts itself as it passes over each hump of the screen bed and is engaged by the succeeding set of blades. In this manner it is discharged in clean condition from the machine. The larger foreign matter that will 105 not work through the holes in the screen bed collect in the pockets on the perforated slide bottoms 15 and can be discharged from time to time into the bottom of the hopper by 110 opening glass door 51 and pulling out the slides 15. When cotton full of bolls is to be cleaned, the boll breaking blades are set at the desired angle and they coöperate with the first series of beater blades to thoroughly 115 break up the bolls and release the cotton to be subsequently cleaned and separated from the bolls in traversing the machine. It is of importance that the beater shafts shall turn at such a high speed as to handle the cotton, as fast as the suction blast will feed it to the machine, beat it down against the screen without permitting any to get to the beater shaft or to accumulate in the cleaner. When 120 the gin suction is interrupted the cotton drops onto the screen concave and into the screen pockets and the hopper door 8 to discharge the refuse therein. On resumption of the gin suction the hopper door 8 closes automatically and the baffles 9, 16 and 17 125 130

One side wall 49 of the hopper immediately below the beam 5 is cut away to form 65 a long narrow opening 50 normally closed by

4
direct the out-rush of air from the hopper upwardly through the screen so that it principally passes through the pockets in the concaves and thus picks up any cotton there in and restores it to the action of the cotton feeding draft through the cleaner.

It is of much importance also that the shafts carrying the beaters be disposed below the main overhead air passage and that 10 the beater blades be so thin as not to reduce materially the velocity of the air current in traversing the cleaner. Through the opening 50 and the hand holes 53 the bottom of the screens and the baffles can be cleaned of 15 lint cotton or foreign matter, and in fact nearly all repairs, adjustments, and treatment can be carried out without taking down the cleaner, but merely by opening the proper door.

20 What I claim as new and desire to secure by Letters Patent, is:—

1. In a cotton cleaner, a casing having its upper portion adapted to be interposed in the suction feed line for a gin, a screening 25 concave, rotary beaters having their blades mounted on axes disposed below the path of the air current through the casing, and a perforated deflector at the intake end of the casing and adapted to deflect the entering 30 cotton downwardly from said air current causing it to pass between said axes and the concave.

2. In a cotton cleaner, a casing adapted to be interposed in a suction feed line for a gin, having at its top a substantially straight undeflected and unrestricted air passage, beaters having axes set substantially below said 35 passage and having their radial blades traversing the passage, screening concaves under the beaters, and means to deflect the entering cotton downwardly toward the axis of the first beater without substantially restricting the passage of the air current therethrough, substantially as described.

40 3. In a cotton cleaner, rotary beaters, a screen concave under the beaters having a transverse pocket along its bottom, a perforated removable slide bottom in said pocket, and a door in the side of the casing giving 45 access to said slide and to the bottom of the screen concave.

45 4. In a cotton cleaner, a casing adapted to be interposed in the suction feed line to the gin and comprising a plurality of beaters, a screening concave bed mounted in the casing below the beaters, there being hand holes in the bed below the screening concave, and a removable glass door in the casing giving access to said hand holes.

50 5. A cotton cleaner comprising a casing adapted to be interposed in the suction feed line to the gin, a plurality of beaters rotatable therein, a hopper bottom having a suction controlled door, a screening concave 55 under the beaters, baffle boards disposed to

concentrate the uprush of air on a restricted transverse bottom zone of the concave.

6. A cotton cleaner comprising a casing adapted to be interposed in the suction feed line to the gin, a series of rotary beaters 70 working therein, screening concaves under the beaters, transverse pockets at the bottom of the concaves, divergent baffle boards depending from the sides of said pockets and disposed to cause the up currents of air 75 to be deflected toward and concentrated under the pockets, and a hopper below the baffle boards having a suction controlled door.

7. In a cotton cleaner, a screening concave 80 comprising a bed having side and end walls, foraminous metal plates attached to said walls which are shaped to provide screening concaves, transverse spaced cross connecting boards at the bottom of each concave to 85 which the foraminous metal plate is attached, and a screen bottom in the pocket formed between said boards.

8. In a cotton cleaner, a screening concave comprising a bed having side and end walls, 90 foraminous metal plates attached to said walls which are shaped to provide screening concaves, transverse spaced cross connecting boards at the bottom of each concave to which the foraminous metal plate is attached, a screen bottom in the pocket formed between said boards, and baffle boards which diverge downwardly from the bottom of said boards.

9. In a cotton cleaner, a screening concave 100 comprising a bed having side and end walls, foraminous metal plates attached to said walls which are shaped to provide screening concaves, transverse spaced cross connecting boards at the bottom of each concave to 105 which the foraminous metal plate is attached, a screen bottom in the pocket formed between the boards, said boards being disposed to converge downwardly, baffle boards which diverge downwardly from the bottom of said boards, and a corresponding baffle board for each concave being substantially longer than the other board and adapted to project under the adjacent shorter baffle board, substantially as described.

110 10. A cotton cleaner comprising rotary beaters and a screen bed there under, said bed having foraminous screening concaves, and a pair of downwardly divergent baffle boards 115 below each concave, the baffle boards being placed to substantially baffle the uprush of air and concentrate it on the bottom middle zones of each concave, substantially as described.

11. In a cotton cleaner, a screen bed forming a concave disposed transversely of the cleaner, one wall of the concave having longitudinal pockets, breaker arms adapted to rest in said pockets, means to adjust the breaker arms relatively to the screen con- 125 130

cave, and rotating breakers working over the concave between the breaker arms, substantially as described.

12. In a cotton cleaner, a rotating beater comprising a shaft and blades thereon, a screening concave under the beater, a rocker shaft carrying integral breaker arms substantially diamond shaped in cross section which are staggered relatively to the beater 10 blades and adjustable to operating position between them, and means to adjust the rocker shaft, substantially as described.

13. In a cotton cleaner, a casing having a hopper bottom with a suction controlled 15 door and a top compartment for the air draft, a removable screen bed comprising reversely sloping end walls adapted to engage and be detachably supported by the hopper walls, a screening concave on the bed, there 20 being registering openings in the side walls of the bed and hopper, a closure for said openings, and rotary beater means working in the air passage above the screening bed, substantially as described.

25 14. A cleaner casing having inlet and outlet openings at opposite ends, rotatable beaters in the casing, bearings for the beaters in the side walls, sections of the side wall above said bearings being vertically removable, and a removable top section in the casing above the beaters, the removable sections forming smooth continuous inner top and side walls for the casing, substantially as described.

30 35 15. In a cotton cleaner casing, rotatable beater elements therein, a screen bed having

transverse pocket members below said beater elements, cross tie bolts spaced midway between and adjacent to the horizontal plane of the axes of the beater elements, and 40 screening concaves under the beater elements formed by foraminous sheets mounted in part on the screen bed and pocket members and bent over the transverse cross tie bolts to form the apex between adjacent concaves, substantially as described. 45

16. A screen bed for cotton cleaners, comprising side walls cut away to form parts of concaves, cross boards mortised at the bases of the curved portions forming a pocket between them, baffle boards secured between the side boards of the bed and diverging downwardly from each pocket, and foraminous material covering the bed and following the curvature of its sides. 50 55

17. In a cotton cleaner, a casing having a hopper bottom, an intermediate screen, and a top section having inlet and outlet openings at opposite ends forming an air passage, a series of rotatable beaters set with 60 their axes below said passage, the beater blades being adapted to traverse the passage proper, and means to deflect the entering cotton downwardly into position to be caught by the initial series of beaters and whipped 65 over the screen bed, the beaters being formed by thin blades which do not substantially obstruct the air blast.

In testimony whereof I affix my signature.
GROVER C. STACY.
